Patented Aug. 22, 1961

191,167

NOVELTY CHEST OR SIMILAR ARTICLE

Stevenson Peter Clark, 3185 Royal Road,
Coconut Grove, Miami, Fla.

Filed July 26, 1960, Ser. No. 61,532

Term of patent 14 years

(Cl. D33—6)

I claim:

The ornamental design for a novelty chest or similar article, as shown.
